UNITED STATES PATENT OFFICE.

FRANK O. PEARSON, OF DENVER, COLORADO, ASSIGNOR OF ONE-THIRD TO BENJAMIN F. HUGGINS AND ONE-THIRD TO JOHN P. McLAIN, BOTH OF DENVER, COLORADO.

ROTARY PUMP.

Application filed June 18, 1921. Serial No. 478,677.

To all whom it may concern:

Be it known that I, FRANK O. PEARSON, a citizen of the United States, residing at the city and county of Denver and State of Colorado, have invented certain new and useful Improvements in Rotary Pumps; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in rotary pumps of the class set forth in the application of John C. Packard, executed May 31st, 1921, Serial Number 475,128, filed June 4, 1921.

20 My improved construction is substantially the same as that disclosed in the said application except that provision is made for positively opening the buckets through the medium of a spring, instead of relying upon 25 gravity and centrifugal force to perform this function.

The invention comprises a casing in which is mounted a rotor which is tangential to an abutment extending thru the bottom of a 30 rotor chamber, each end of the said chamber being provided with crescent shaped members which merge into the opposite extremities of the abutment, the abutment and crescent shaped members being cast integral with the 35 casing.

The rotor is provided with pockets and adjacent these pockets are mounted oscillatory buckets which are adapted to move into the pockets as any bucket engages the crescent 40 shaped members and moves toward the abutment. As soon as the bucket leaves the abutment it begins to open by virtue of the action of the spring which, as shown in the drawing, is mounted on a bolt which is fast 45 in the bucket and passes through a slot formed in the adjacent part of the rotor, the bolt having an adjustable nut whereby the outward swing of the bucket may be limited in order to prevent undue friction between 50 the bucket and the inner surface of the rotor chamber.

Having briefly outlined my improvement I will proceed to describe the same in detail, reference being made to the accompany-

ing drawings in which is illustrated an embodiment thereof.

In this drawing:

Fig. 1 is a detail view of the rotor with the buckets removed;

Fig. 2 is an elevation of the rotor looking 60 at right angles to Fig. 1;

Fig. 3 is a detail view of one of the buckets;

Fig. 4 is an elevation of the bucket looking 65 in the direction of arrows 4 Fig. 3;

Fig. 5 is a detail view of one of the discs with which the opposite ends of the casing are provided;

Fig. 6 is a section taken on the line 6—6 70 Fig. 5;

Fig. 7 is a view of the pump with one of the heads and the adjacent end disc removed, the casing and rotor being also shown partly in section;

Fig. 8 is a view partly in elevation and 75 partly in section, the section being taken on the line 8—8 of Fig. 7.

The same reference characters indicate the same parts in all the views.

Let the numeral 5 designate a cylindrical 80 casing provided with end heads 6 secured thereto by bolts 7 or other suitable fastening devices. Also secured to the opposite ends of the cylindrical portion of the casing, which are counterbored for the purpose as 85 shown at 8, are two discs 9 which engage the counterbores of the casing and are clamped between the heads and the shoulders formed by said counterbores of the casing. This casing is provided with an inlet 10 and an outlet 90 12 for the water. The cylindrical part of the casing is provided on its interior with two crescent shaped members 13 which merge at their extremities into a bottom abutment 14.

Extending through the center of the casing and journaled in hubs 15 is a shaft 16 to which is also applied stuffing boxes 17 in order to make the casing watertight. Upon this shaft is mounted a rotor 18 which is so 100 constructed and arranged that it rotates with the shaft and is tangential to the abutment, there being, however, a space between the rotor and the inner surface of the casing at all other points. This rotor is provided 105 with pockets 19 which are recessed at 20 to receive the bearing edges 21 of buckets 22, the extremities 23 of the bearing edges ex-

tending slightly beyond the ends of the buckets proper and engaging recesses 24 formed in the discs 9. By virtue of this construction the buckets are allowed to swing 5 into and out of the pockets of the rotor, while at the same time they are retained in proper relation to the rotor and the casing when the pump is in use. The discs 9 are secured to the rotor by suitable fastening 10 devices as stud bolts 25. Each bucket is provided with a bolt 26 which is fast therein and extends through the slot 27 formed in a web 28 of the rotor which separates the pocket 19 from a cored-out place 29 in the 15 rotor. Each of these bolts is threaded at its extremity remote from the bucket and provided with a nut 30 for purposes of adjustment whereby the outer edge 31 of each bucket is prevented from bearing against the 20 adjacent wall of the casing to produce undue friction.

My improvement consists in applying to the bolts 26 between the buckets and the webs 28 of the rotor, spiral springs 32 which 25 are under tension to positively move the buckets out of the pockets into the space between the rotor and the inner surface of the casing, as soon as the buckets leave the abutment.

From the foregoing it will be understood 30 that by the employment of the bolts and the springs, the buckets are prevented from being moved outwardly against the inner surface of the casing with sufficient force to 35 produce undue friction, while at the same time the springs 32 act upon the buckets to move them outwardly and cause them to properly perform their function even though the rotor might be moving so slowly that the 40 buckets would not open automatically by gravity and centrifugal force.

From the foregoing description the use 45 and operation of my improvement will be readily understood. When the pump is in use it is so located that the water or other liquid or fluid to be pumped, enters the rotor chamber through the opening 10 and is 50 discharged through the opening 12. When the pump is in use the rotor is moving in the direction indicated by the large arrow in Fig. 7. As each bucket leaves the abutment 14, it is caused to gradually open as the space between the rotor and the inner sur-

face of the casing enlarges, this opening movement being positively effected by the 55 spring 32, the bucket, however, being held by its bolt 26 in proper position with reference to the rotor and the inner surface of the casing to prevent undue friction as heretofore described. As the bucket leaves the inlet openings 10, it carries the liquid with it and finally forces it out of the opening 12 which is in communication with the conduit through which the water acted on by the pump is to be discharged or raised. As soon 60 as any bucket reaches the extremities of the crescent shaped members 13 adjacent the discharge opening of the casing, the buckets will be gradually moved inwardly into the pockets until the abutment is 65 reached, and as any bucket passes the abutment it begins to open again by virtue of the recoil of its spring 32. It will be understood that the springs 32 might be employed 70 to open the buckets in the absence of the bolts 26, in which event it would be necessary to have recesses formed in the buckets of the adjacent webs 26 in which the extremities of the spiral springs could be seated. It is preferred, however, to use the 75 springs in connection with the bolts for the reasons heretofore given.

I claim:

1. A rotary pump comprising a casing, a rotor therein having pockets, oscillatory 85 buckets connected with the rotor to move into and out of said pockets, means for positively imparting the outward movement to the buckets and cooperating means for limiting their outward travel comprising 90 bolts anchored in the buckets and movable in an opening formed in the rotor.

2. A rotary pump comprising a casing, a rotor mounted therein having pockets, oscillatory buckets mounted to move in and out 95 of said pockets and means for controlling the outward movement of the buckets comprising bolts anchored in the buckets and movable in openings formed in the rotor; means applied to the bolts for limiting the 100 outward movement of the buckets and springs mounted on the bolts between the buckets and the walls of the pockets for positively imparting the outward movement.

In testimony whereof I affix my signature. 105

FRANK O. PEARSON.
